UNITED STATES PATENT OFFICE.

GEORGE LIGOWSKY, OF CINCINNATI, OHIO, ASSIGNOR TO THE LIGOWSKY CLAY-PIGEON COMPANY, OF SAME PLACE.

FLYING TARGET.

SPECIFICATION forming part of Letters Patent No. 311,768, dated February 3, 1885.

Application filed September 11, 1883. (No model.)

To all whom it may concern.

Be it known that I, GEORGE LIGOWSKY, a citizen of the United States, residing at Cincinnati, in the county of Hamilton and State 5 of Ohio, have invented certain new and useful Improvements in Flying Targets, of which the following is a specification, reference being had therein to the accompanying drawings.

10 This invention relates to that class of flying targets commonly known as "clay pigeons," on account of such devices being usually made of clay or earthenware, which material is so tempered or hardened by baking 15 or burning in a kiln as to cause the "pigeon" to break or shatter when struck with shot or other similar projectiles, as described in the various patents previously granted to me.

The present improvement consists in 20 constructing a saucer or cup shaped target without slot, tongue, lug, or other lateral projection that might impede its whirl or axial rotation through the air, or which would involve precision and loss of time in applying 25 the target to the trap or other "sender." This saucer-shaped target or pigeon is put on the market as a finished and integral article for sale, and is to be thrown from the trap and given its whirl by any suitable permanent or enduring instrumentality—as, for 30 instance, and advisably, by a spring bar or clip temporarily applied to said target for its destructive use, and retained for application to other pigeons as they in their turn are to be thrown. Said spring-bar may be of any 35 appropriate shape; but I prefer to use the device seen in the application filed by myself in the United States Patent Office, August 11, 1883, No. 103,518.

40 In the annexed drawings, Figures 1, 2, 3, and 4 are axial sections of four different forms of my saucer-shaped flying target.

As seen in Fig. 1, the target or pigeon consists of a short cylindrical body or shell, 45 A, having a crowning top, B, and, if desired, a circumferential bead or molding, C, at the margin of said cylinder. The target is made of baked clay or earthenware, or other fragile material or composition of materials capable of being readily punctured, or cracked when

struck with shot. Furthermore, said target must be comparatively light and thin, and must be constructed without a slot or a lug, tongue, or other lateral projection of any kind whatever.

55 As seen in Fig. 2, the crowning top B is used; but the body, instead of being exactly cylindrical, as represented in Fig. 1, inclines outwardly at D, and then slopes inwardly at E, thereby causing the peripheral rim of the target to have the shape of an obtuse angle in cross-section.

In Fig. 3 the crown B is joined to an outwardly-flaring rim, F, that may be either curved, as shown, or it may be simply a 60 straight incline or pitch, as represented at D in Fig. 2.

Fig. 4 represents the crown B as merging into a concave rim, G, of any appropriate degree of curvature. Other and almost innumerable modifications of the form of this saucer or cup shaped target will readily suggest themselves to any person who is at all familiar with the use of such devices. Which-ever form is selected allows the spring-bar 70 previously alluded to, or other device for imparting the whirling motion in the act of throwing, to be engaged with the rim, or otherwise applied to the target at any point along its periphery without special adjustment or 75 forethought; and, owing to the symmetrical shape of the pigeon, it can be cheaply manufactured by the process described in the patent granted to me August 23, 1881, No. 246,161; or said target may be made by any 80 of the known processes or machines commonly employed in potteries, &c.

85 As a matter of finish or ornamentation, and also to prevent shot glancing therefrom, the outer surface of the target may be ribbed and 90 grooved or varied in contour without departing from the saucer, cup, or dish form herein described.

95 I claim as my invention—

1. A saucer or cup shaped flying target formed as a thin shell of clay or similar material suitably hardened, without slot, tongue, or projection, substantially as and for the purpose specified, as a new article of manufacture.

100 2. A saucer or cup shaped flying target

having a peripheral flange of uniform thickness circumferentially, and without slot or tongue, or provision for the attachment of a tongue or extraneous or special handle for 5 propulsion, which might constitute an impediment to the axial rotation of the target, substantially as specified.

In testimony whereof I affix my signature in presence of two witnesses.

GEORGE LIGOWSKY.
